UNITED STATES PATENT OFFICE.

JOHN S. LEARY, OF NORTH CAMBRIDGE, MASSACHUSETTS.

ARCH-SUPPORTING PAD.

1,091,673.

Specification of Letters Patent. Patented Mar. 31, 1914.

Application filed October 29, 1913. Serial No. 797,990.

To all whom it may concern:

Be it known that I, JOHN S. LEARY, a citizen of the United States, residing at North Cambridge, in the county of Middlesex and State of Massachusetts, have invented new and useful Improvements in Arch-Supporting Pads, of which the following is a specification.

This invention relates to a pad adapted to be inserted in a shoe and having for its object to support the arch of the foot.

The object of the invention is further to distribute the weight of the body equally over the foot of the wearer and thereby relieve or prevent fallen arch or other foot troubles.

The object of the invention is further to provide a device of the character set forth which shall be light, cheap, resilient and durable and which can be washed without injury to the same.

To secure these ends, the pad is made of a piece of felt having a slit or incision between the upper and lower surfaces which extends from the heel portion to the front of the arch of the foot or to the front of the shank portion of the shoe. This slit or incision is stuffed with curled hair and made of the right shape to conform to the arch of the foot.

The device is intended to be worn in the shoe and held in place by the pressure of the foot of the wearer. Being composed of soft felt and having resiliency imparted thereto by the curled hair the result is a device of the character set forth, which is easy and comfortable to the foot and supports the arch of the foot without subjecting it to discomfort.

40 The felt presents a soft surface to contact with the foot and the cushion of hair supplies sufficient resiliency to support the foot with a yielding pressure thereagainst as distinguished from the devices designed for the same purpose and made of metal or leather.

The invention consists of an arch supporting pad as hereinafter described in the specification and particularly as pointed out in the claims.

50 Referring to the drawings: Figure 1 is a plan view of an arch supporting pad embodying my invention and adapted to be used in a shoe for the left foot. Fig. 2 is a section of the piece of felt from which the pad is manufactured, showing the same slit and the portion above the slit turned up-

wardly in dotted lines in the position which it would assume when the curled hair is being inserted within the slit portion. Fig. 3 is a section taken on line 3-3 of Fig. 1. Fig. 4 is a section taken on line 4-4 of Fig. 1.

Like numerals refer to like parts throughout the several views of the drawings.

In the drawings, 6 is a piece of felt, the contour of which is of the correct shape to fit the interior of the shoe in which it is to be used, the same being designed to extend from the rear of the heel portion of the shoe to the front part of the shank portion of said shoe. This piece of felt is slitted intermediate its upper and lower faces as at 7, (Fig. 2) thus forming an upper flap 8 and a lower flap 9. The upper flap is then turned upwardly into approximately the position illustrated in dotted lines Fig. 2 and the curled hair 10, which forms a cushion, is inserted between the upper and lower flaps, said flaps being sewed together to close said slit portion by stitches 11 adjacent to the upper edge of the pad. The inner edge of the slit 7 is formed on a curve and may be stitched at 12 in a curved line, the cushion 10 being inclosed within that portion of the pad bounded by the lines 11 and 12 and terminating adjacent to the rear of the heel portion of the pad at one end thereof and adjacent to the front edge 13 of the pad at the other end thereof. The cushion of curled hair 10 extends therefore from near the end of the rear of the heel portion to the front part of the shank portion of the shoe and also extends from the inner edge of the pad substantially two-thirds of the distance thereacross.

As illustrated in Figs. 3 and 4 sufficient hair is inserted between the upper and lower flaps 8 and 9 to form a cushion and said cushion is so formed or shaped as to fit and support the arch of the foot.

The pads are made to fit right and left shoes. The pad shown in Fig. 1 of the drawings is adapted to fit a left shoe.

I claim:

1. An arch supporting pad adapted to be inserted in a shoe and comprising a single piece of felt slit intermediate its upper and lower faces, and a cushion of hair inserted within said slit portion.

2. An arch supporting pad adapted to be inserted in a shoe and comprising a piece of felt slit intermediate its upper and lower

- faces, and a cushion of hair inserted within said slit portion, said slit portion being closed by stitches extending along one edge of said pad and arranged to hold said hair in position therein.
3. An arch supporting pad comprising a piece of fabric formed to fit the interior of a shoe and arranged to extend from the rear of the heel portion to the front part of the shank portion of said shoe, said pad being slit intermediate its upper and lower faces from one side thereof partly thereacross and longitudinally thereof for a portion of its

length, and a cushion of hair interposed within said slit portion, said slit portion being closed by stitches extending along one edge of said pad and arranged to hold said hair in position therein. 15

In testimony whereof I have hereunto set my hand in presence of two subscribing witnesses. 20

JOHN S. LEARY.
